UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

DESIGN FOR A LANTERN-BRACKET.

SPECIFICATION forming part of Design No. 30,491, dated April 4, 1899.

Application filed January 18, 1899. Serial No. 702,597. Term of patent 14 years.

To all whom it may concern:

Be it known that I, FRANK RHIND, a citizen of the United States, residing at Bridgeport, Connecticut, have invented and produced a new and original Design for a Lantern-Bracket, of which the following is a specification.

The accompanying drawing is a perspective view of a lantern-bracket, showing my design.

As shown in the drawing, the general outline of my design is in the form of a pair of

upwardly and forwardly extending sides or bars 1, united at their upper ends 2 and having rearwardly-extending lower portions 3, the ends 4 of which are turned inwardly. 15

What I claim is—

The design for a lantern-bracket herein described and shown.

FRANK RHIND.
